CLAIM

We claim the ornamental design for a display screen or portion thereof with graphical user interface for water delivery components, as shown and described.

DESCRIPTION

FIG. 1 is a front view of a display screen or portion thereof with graphical user interface for water delivery components showing our new design; and, FIG. 2 is another front view thereof.

The ornamental design which is claimed is shown in solid lines in the drawings. In the drawings the dot-dash broken lines are for the purpose of illustrating the boundaries of the claim. The dash-dash broken lines are for the purpose of illustrating the display screen, environmental structure (the water delivery component) and portions of the graphical user interface that forms no part of the claimed design.
